DOOR OPERATING MECHANISM FOR MIXING MACHINES

Filed Sept. 10, 1928 2 Sheets-Sheet 2

Inventor:

Alfred C. Christensen.

Charlevoix MI

UNITED STATES PATENT OFFICE

ALFRED C. CHRISTENSEN, OF CHICAGO, ILLINOIS, ASSIGNOR TO NATIONAL ENGINEERING COMPANY, OF CHICAGO, ILLINOIS, A CORPORATION OF ILLINOIS

DOOR-OPERATING MECHANISM FOR MIXING MACHINES

Application filed September 10, 1928. Serial No. 304,990.

This invention relates to door operating mechanism for mixing machines, and concerns itself primarily with a novel arrangement whereby the doors may be manually actuated in one direction and power operated in the opposite direction.

The invention comprises a novel structure and combination of parts hereinafter described and more particularly pointed out and 10 defined in the appended claims.

In the accompanying drawings which illustrate a preferred embodiment of this invention and in which similar reference numerals refer to similar features in the different 15 views.

Figure 1 is an elevational view of a mixing machine involving this invention illustrating merely the mixing receptacle.

Figure 2 is a view similar to Figure 1 with 20 parts broken away to more clearly illustrate the discharge doors on the bottom of the receptacle.

Figure 3 is an enlarged fragmentary sectional view taken on the line III—III of 25 Figure 1.

Figure 4 is an enlarged fragmentary sectional view taken on the line IV—IV of Figure 1 looking in the direction of the arrows.

In referring to the drawings which illustrate an embodiment of this invention, the reference numeral 1 indicates the mixing receptacle of the machine which is provided with a bottom 2. In the present instance the bottom of the mixing receptacle is provided 35 with a pair of discharge openings 3 which are adapted to be closed by discharge doors 4. Adjacent the inner margin of each door opening 3 there is a rod 5 which is journaled in suitable depending lugs or bearings upon the bottom of the receptacle as shown in Figure 40 3. Each door is provided with suitable hinge brackets or castings 6 secured to the bottom face thereof, and the inner ends of these castings or brackets 6 are rigidly secured to the rods 5 whereby the rotation of the rods will cause a swinging movement of the doors.

Each rod 5 extends beyond the periphery of the bottom of the mixing chamber as shown in Figure 3. An arm 7 is rigidly attached to the extended end of each rod 5.

Each arm 7 is connected by an adjustable link 8 with a disc 9 which is rotatably mounted upon a driving shaft or power shaft 10 which is journaled in the supporting legs 11 of the receptacle. It might be mentioned that the 55 shaft 10 is designed to drive the mechanism for the mixing machine, and to this end it is shown as provided with a gear 10^a for operating the same. The aforementioned disc 9 is provided with a clutch drum 12 adapted for 60 cooperation with a clutch member 13 splined or slidably keyed upon the shaft 10. The clutch member 13 is provided with a groove for receiving a yoke lever 14 which is pivoted intermediate its ends to a bracket 15 extending 65 from the receptacle. The lever 14 may be swung inwardly or outwardly to frictionally engage the clutch member 13 with the drum 12 whereby the disc 9 becomes clutched to the shaft for rotation with the driving 70 shaft 10.

The aforementioned disc 9 is provided with a laterally extending lug or shoulder 16 which is best shown in Figure 1. This lug 16 is adapted to be engaged by a plunger rod 17 which is slidably mounted in keepers 18 upon a plate 19 secured to the receptacle. The operating rod 17 is provided with an adjustable nut 20 below one of the keepers 18 for limiting the upward movement of the 75 lug 16 and thereby limiting the rotation of the disc 9 in a clockwise direction.

In the operation of the heretofore described mechanism, let it be assumed that the parts are in the position shown in Figure 1 and that it is desired to open the discharge doors for discharging the contents of the mixing receptacle. In order to accomplish this, the operator will slide the plunger 17 downwardly and rotate the disc 9 in an anti-clockwise direction as viewed in Figure 1, independently of the shaft 10. This rotation of the disc 9 will swing the arms 7 downwardly as shown in dotted lines in Figure 2, and since the arms 7 are rigidly connected with the rods 5 the latter will be rotated for swinging the discharge doors downwardly into open position as shown in dotted lines in Figure 2.

Now if it is desired to close the doors, the

operator will shift the lever 14 to engage the clutch 13 with the drum 12 of the disc 9, thereby clutching the disc 9 to the shaft 10. As the shaft 10 normally rotates in a clockwise direction it will rotate the disc 9 in the same direction and swing the doors to their closed position through the instrumentality of the links 8 and arms 7. Of course, the disc 9 can only be rotated by the shaft 10 until it is stopped by the plunger rod 17. At such time the friction clutch 13 may be disengaged from the disc 9 or if it is not disengaged at the proper time a certain slippage of the clutch may occur.

15 From the foregoing it will be obvious that a novel door mechanism has been provided whereby the door may be manually open for discharging the contents of the container and in which the doors may be closed by power taken from the operating shaft of the machine.

I am aware that many changes may be made and numerous details of construction may be varied through a wide range without departing from the principles of this invention, and I therefore do not purpose limiting the patent granted hereon, otherwise than necessitated by the prior art.

I claim as my invention:

30 1. In a mixing machine having a bottom, a pair of doors in said bottom, a rod for supporting each door for turning movements, an arm on each rod, a driving shaft, a disc having a clutch face rotatably mounted upon said shaft, a rigid link connecting each arm with said disc, said disc having a lug, an actuating member engageable with said lug for turning said disc to open said doors, a clutch splined upon said shaft, and means for engaging said clutch and disc to move said disc in a direction to close said doors.

2. In a mixing machine having a bottom, a pair of doors in said bottom, a rod for supporting each door for turning movements, an arm upon each rod, a shaft, a disc freely rotatable upon said shaft, a rigid link connecting each arm and said disc, said disc having a lug, and a plunger for engaging said lug for operating said disc to open the doors.

3. In a mixing machine having a bottom, a pair of doors for said bottom, a rod for supporting each door for turning movements, an arm on each rod, a shaft, a disc rotatably mounted upon said shaft, a rigid link connecting each arm with said disc, a clutch splined upon said shaft, and means for sliding said clutch into engagement with said disc to move the same in a direction to close said doors.

4. In a mixing machine having a bottom, a pair of doors in said bottom, a rod for supporting each door for turning movements, a driven shaft, a rigid connection between each arm and said shaft, manually actuatable

means for operating said connections independently of said shaft to open said doors, and means for clutching said connections to said shaft for operation thereby to close said doors.

5. In a mixing machine having a bottom with a door opening, a door for closing said opening, a rod for supporting said door for turning movements, a driven shaft, a member rotatable upon said shaft, a rigid connection between said arm and member, means for manually operating said member to open said doors, and means for clutching said member to said shaft for operation thereby to close said doors.

6. In a mixing machine comprising a mixing receptacle having a discharge opening, a door for closing said opening, means for supporting said door for turning movements, a driving shaft, a member freely rotatable thereon, a rigid connection between said door and member, means for manually operating said member independent of said shaft, and means for clutching said member to said shaft for operation thereby.

7. In a mixing machine embodying a receptacle having a discharge opening, a door for closing said opening, a driving shaft, a disc freely rotatable upon said shaft, a rigid connection between said disc and door, means for manually operating said disc, and means for clutching said disc to said shaft for operation thereby.

8. In a mixing machine embodying a mixing receptacle having a discharge opening, a door for closing said opening, a power operated device and rigid means connecting said door and power operated device for operating said door, a lever for releasing said means, and a manually actuatable member for operating said means.

9. In a machine of the character described, embodying a receptacle having a discharge opening, a door for closing said opening, a power driven shaft, a rigid connection between said door and shaft, means for manually actuating said connection independent of said shaft for opening said door and means for clutching said connection to said shaft for closing said door.

10. In a machine of the character described embodying a receptacle with a discharge opening, a door for closing said opening, a power driven shaft, a disc freely revoluble upon said shaft, a rigid connection between said door and disc, means for clutching said disc to said shaft, said disc having a shoulder, and a manually operated member for engaging said shoulder for operating said disc independent of said shaft.

11. In a machine of the character described embodying a receptacle with a discharge opening, a door for closing said opening, a power driven element, a rigid connection between said door and element, means for op-

erating said connection independent of said element and means for clutching said connection to said element.

12. In a mixing machine having a pair of discharge openings, a rod trunnioned adjacent each of said openings, a door secured to each of said rods for turning movement, an arm secured to each of said rods, a driving shaft, a disc having a radial lug rotatably mounted upon said shaft, a rigid link connecting said lug to said arm, and clutch means for connecting said disc to said shaft for moving said lug past a dead center position for maintaining said doors in a closed position.

13. In a mixing machine having a pair of discharge openings, a rod trunnioned adjacent each of said openings, a door secured to each of said rods for a turning movement, an arm secured to each of said rods, a driving shaft, a rotatable disc on said shaft, a rigid link connecting each arm with said disc, clutching means for connecting said shaft to said disc for rotating the disc to a position where the doors will be closed and locked, and plunger means engaging said disc for manually rotating the same to a position for releasing the doors.

In testimony whereof I have hereunto subscribed my name at Chicago, Cook County, Illinois.

ALFRED C. CHRISTENSEN.
